UNITED STATES PATENT OFFICE

1,988,578

ABRADING MACHINE

William Scrimgeour, Washington, D. C.

Original application January 4, 1933, Serial No.
650 157. Divided and this application Septem-

Serial No. 689,121

4 Claims.
This invention relates to abrading machines

and particularly to the construction and mounting of an abrading roll adapted for heavy work. This application is a division of my copending application "Abrading machine", Serial No. 1032.

50,157, filed January 4, 1933.
An object of the invention is to provide an

An object of the invention is to provide an abrading machine including an abrading roll in the form of a plurality of disks on a mandrel and secured thereto by pressure sleeves which are slidable upon the mandrel. A further object is to provide an abrading roll including a plurality of disks mounted upon a mandrel, and bearing sleeves mounted on the mandrel and, preferably, 10 acting as pressure sleeves clamping said disks in place.

These and other objects and advantages of the invention will be apparent from the following specification when taken with the accompanying drawing in which:

Fig. 1 is a sectional end elevation of an abrading machine embodying the invention; and

Fig. 2 is a transverse section through the abrading roll, as taken on line 2-2 of Fig. 1.

25 In the embodiment illustrated, which, it will be understood, is susceptible of various modifications and changes without departing from the spirit of the invention, the machine has an appropriate framework with and in which the various elements comprising the several elements and parts hereinabove referred to are operatively assembled.

This framework includes supports 1 and bearings 2 for the work supporting means or roller 3 and guide members 4 in which are mounted reciprocal bearing members 5 having suitably bushed bearings 6 in which are rotatably and reciprocably mounted the abrading means or roller 7 more particularly described hereinafter.

40 The weight of the abrading roll 7 is such that it is moved, by gravity, toward the work supporting roller 3, and thus into appropriate abrading contact with the work supported upon the roller 3, but, if desired, springs or other pressure exerting means may be employed for forcing it to the work.

45

In order that the desired delicate adjustment of the pressure of the abrading roll 7 upon the work may be attained, the bearing members 5, 50 which support the abrading roll, are provided with cushioning supporting means, preferably in the form of cylinders 8 having pistons 9, the rods or stems 10 of which engage with and support the bearing members 5. Hydraulic pressure is supplied to the cylinders through pipes 11 which

lead to an accumulator, not shown, and the machine may, and preferably does, include mechanism for automatically locking the abrading roll in raised position when there is no work between the abrading roll 7 and the work supporting roll. 5

Appropriate mechanism for thus supporting the abrading roll clear of the bottom roll 3 is described and claimed in my copending application. The abrading roll comprises a plurality of simi-

The abrading roll comprises a plurality of similar abrading disks 12 of known type having fixed therein metal hubs 13. These disks are arranged upon a mandrel 14 in intimate contact and mounted for rotation therewith by suitably keying their hubs 13 to the mandrel keyway 15, as shown in Fig. 2. To hold the disks 12 in abrading roll forming assembly upon the mandrel and at the same time provide adequate bearings therefor in the bushings 6 of the bearing members 5, sleeve members 16, 17 are provided. The sleeve member 16 is assembled upon the mandrel 14 before any of the disks are slipped thereon and abuts against a hexagonal or other non-cylindrical head 18 thereon. The other sleeve member 17 is slipped onto the other end of the mandrel after all of the disks are in place thereon and is forced home against the end disk by a cap screw 19 which engages the screw threads of a bore 20 in the adjacent end of the mandrel. Thus, the abrading disks are assembled on the mandrel in intimate contact to form the abrading roll.

The abrading roll is rotated by means of pulleys 21 keyed to the sleeve members 16, 17 and belts 22 driven by pulleys 23 fixed on the shaft 24 of a motor 25 carried upon the bridge 26 which is carried by the bearing members 5. Axial reciprocation of the abrading roll is accomplished by means of a lever 27 having a pivot bearing 28 in a fixed bracket 29 and provided with an opening 30 carrying pins 31 which engage a suitable annular recess 32 adjacent to the outer end of the sleeve member 17. The free end of the lever 27 is provided with a longitudinal slot 33 which receives the pin 34 of a crank arm 35 on a shaft 36. The shaft 36 is rotated by a worm and wheel gearing 37, 38, the worm 37 of which is mounted on a back shaft 39 driven by gears 40, and 41, from the motor shaft extension 24. 16, 17, 50

It will be noted that the sleeves 16, 17 provide bearing surfaces which are substantially larger than the bearing surfaces obtained when the mandrel is mounted directly in the bearings 6, as has been the prior practice. Furthermore, the omission of the usual clamping nuts at each 55

end of the series of disks makes it possible to reduce the space required between members 5 for a roll of any given length. The mandrel 14 may be of a type of steel best adapted for driving the abrading roll, and the sleeves 16, 17 may be of the same steel or of other metal best suited for their double functions of clamping means and bearing sleeves.

It will be apparent that the invention is not limited to the particular embodiment herein illustrated and described, and that various changes may be made in the size, shape and construction of the several parts without departing from the spirit of my invention as stated in the following claims.

I claim:

1. In an abrading machine, an abrading roll comprising a cylindrical mandrel, a plurality of abrading members mounted upon said mandrel, and means for pressing said abrading members into intimate roll-forming relationship upon said mandrel; said means including sleeve members slidably mounted upon the opposite ends of said mandrel and bearing against the abrading members, and pressure applying means including an element adjustably secured to said mandrel and

bearing against one of said sleeve members to force them toward each other.

2. An abrading roll as claimed in claim 1, wherein said sleeve members have cylindrical external surfaces and constitute the bearing members for rotatably mounting the abrading roll in an abrading machine.

3. In an abrading machine, a rotary and reciprocable abrading roll comprising a mandrel and a plurality of similar abrading members mounted upon said mandrel, means for pressing said abrading members into intimate roll-forming relationship upon said mandrel; said means including sleeve members slidably mounted upon opposite ends of said mandrel and bearing against an adjacent abrading member, and pressure applying elements at the ends of and one adjustable axially of said mandrel, said elements bearing against said sleeve members to force them toward each other, said sleeve members having external surfaces providing bearings for rotation and reciprocation of said abrading roll.

4. An abrading roll as claimed in claim 3, in combination with driving means keyed to and slidably axially along each of said sleeve members.

WILLIAM SCRIMGEOUR.
